GRILLE

Edward L. Anderson, Grosse Isle, Mich., assignor
to American Blower Corporation, Detroit,
Mich., a corporation of Delaware

Application April 3, 1936, Serial No. 72,571

8 Claims. (Cl. 98—114)

My invention relates generally to grilles for the diffusion of air and more particularly to stamped sheet metal grilles.

One of the objects of my invention is to provide a new and improved grille for diffusing air and one which is inexpensive to manufacture.

Another object of my invention is to provide a grille constructed of sheet metal so that it can be manufactured at low cost, and having air passages defined by portions formed out of the grille to provide for efficient diffusion of air.

Another object of my invention is to provide a grille of the above mentioned character through which air may be discharged under pressure, and at high velocity, without resultant noise.

Another object of my invention is to provide a grille for the diffusion of air and one which will induce rapid mixing of the air discharged therethrough with the room air at the face of the grille.

The invention consists in an improved grille construction, to be more fully described herein-after and the novelty of which will be particularly pointed out and distinctly claimed.

In the accompanying drawing, to be taken as a part of this specification, I have fully and clearly illustrated my invention, in which drawing—

Figure 1 is a view in front elevation of my grille;

Fig. 2 is an enlarged fragmentary view shown in cross section and taken along the line 2—2 of Fig. 1, and

Fig. 3 is a view similar to Fig. 2, of a portion of my grille for illustrating how flow of air is affected by my grille.

Referring to the drawing by characters of reference the numeral 1 designates in general my grille, the particular type of grille shown being adapted for the diffusing of air discharged into a room. The grille 1 is constructed of a single sheet of sheet metal, or plate 2, by a stamping operation, one side of the plate, as at 3, constituting the face of the grille. Preferably the plate 2 is formed having a continuous flange 4 along its side and end edges and which extends rearwardly of the face of the grille and preferably flares outwardly, as shown. The grille 1 is adapted to be fixed to a wall 5 of a room and in overlying relation to an opening 6 in the wall with the edge of the flange 4 in engagement with the wall surface of the room side. Preferably the plate 2 is provided with apertures 7 for receiving screws 8, or other suitably attaching means for securing the grille to a wall of a room, and preferably the apertures 7 are counter-punched as

shown, so that the screw heads can be substantially flush with the face of the grille.

The plate 2 is provided with a plurality of spaced openings or apertures 10 for the passage of air and, in the present instance, these openings are of elongated form and arranged with their longitudinal axes extending vertically with relation to the top and bottom edges of the grille. Formed out of the plate 2 around each of the openings 10 there is a continuous annular flange 10 formed having a portion 11 which extends rearwardly of the face of the grille, and having a reentry or rebent portion 12 disposed within the confines of the flange portion 11. The inner wall surfaces of the rebent portions 12 define a plurality of passages 13 for the discharge of air into a room. The rebent portions 12 are in spaced relation to their respective flange portions 11 forming outwardly facing channels 15. Preferably the outer edges of the rebent portions 12 terminate flush with the face of the grille to provide a finished and neat appearing structure. The portion of the flange between the portion 11 and the rebent portion 12 is preferably rounded, as at 14, to induce the flow of air into the flow passage 13. A sheet of sound deadening material 15, such as felt, is fixed to the rear face or back of the grille 1 and has a plurality of elongated apertures or cutouts for receiving the rearwardly extending flanges around each opening. The sound deadening material 15 prevents the impingement of the air against the flat surfaces between openings in the grille and may be glued or otherwise suitably secured to the grille plate.

By reason of the rounded edges 14 defining the inlet openings of the air passages, air will be drawn and induced to flow into said passages at angles to the grille plate, as indicated in Fig. 3. Also, the rounded edges defining the inlets have the effect of a dam and cause the air entering the passages to crowd thereinto and to be evenly distributed. In addition, the rounded edges 14 provide for a gradual reduction in the velocity of the air as it enters the grille passages with the result that noise or whistling of the air, due to abrupt changes in its velocity, is substantially eliminated. In grilles having openings defined by square edges it has been found that the effective capacity of the openings is only about 60% whereas in my grille having the rounded edges 14, the effective capacity of the openings is substantially 90%. Air discharging into the room causes a low pressure area at or adjacent the face of the grille, into which area the room air flows and is drawn into the air streams. In my grille 55

the annular outwardly facing channels 15 provide spaces back of the air discharge openings in which the pressure is reduced by the velocity of the discharging of air streams. Room air thus flows into the spaces defined by the channels around each opening and is drawn into the air streams substantially parallel to the streams of primary air.

By providing a grille constructed of sheet metal 10 it will be understood that it can be constructed very economically, and by forming the discharge passages by the flanges formed out of plate 2 and having the rebent portions providing rounded edges defining the openings to the passageways, 15 a grille is provided which is both economical in construction and efficient in the discharge and diffusion of air.

What I claim and desire to secure by Letters Patent of the United States is:

20 1. A grille for the discharge of air comprising a plate member having a plurality of openings therein for the passage of air, said plate having a continuous flange around each opening with said flanges each having a reentry portion defining passageways for air.

25 2. A stamped grille for the discharge of air comprising a sheet metal plate having a plurality of openings for the passage of air, said sheet metal plate having a continuous flange around each opening and a rebent continuous portion defining passageways for air.

30 3. A stamped sheet metal grille comprising a plate member having a plurality of openings therethrough, said plate having a bent continuous lateral flange portion around each opening and a continuous rebent portion in spaced relation to said flange portion and defining passageways for air.

35 4. A sheet metal grille for the discharge of air 40 therethrough comprising a plate member having a plurality of openings through which the air passes, one side of said plate constituting the face of the grille, said plate having a continuous flange portion around each opening and extending rearwardly of the face of the grille and having a reentry portion extending toward the face of said grille and terminating substantially flush therewith, each of said reentry portions defining a passageway for air.

5. A sheet metal grille for the discharge of air therethrough comprising a single sheet metal plate having a plurality of openings therein for the passage of air, one side of said sheet metal plate constituting the face of the grille, said sheet metal plate having a continuous flange portion around each opening and extending rearwardly from the face of the plate, said flange portions each having a rebent continuous flange portion in spaced relation thereto and extending toward and terminating substantially flush with the face of the grille and forming outwardly facing channels around each opening, said rebent portions defining said openings with the portion between the flange portion and the rebent portion of each opening being rounded to induce air to flow through the openings. 5

6. A grille structure for the diffusion of air comprising a sheet metal plate member having a plurality of spaced openings therethrough for air, one side of said plate member constituting the face of the grille, said plate member having a rearwardly extending annular flange portion around each opening and an annular rebent portion disposed in spaced relation to and within the confines of said rearwardly extending portion and extending toward the face of the grille, said rebent portions defining passageways for air with the wall portions between the rearwardly extending flange portions and the rebent portions 30 defining the inlets to the passageways and being rounded to induce flow thereinto. 25

7. A grille for diffusing air comprising a plate member having a plurality of openings therethrough, said plate member having a flange around each of said openings with said flanges each having a reentry portion defining passageways for air. 35

8. A grille for diffusing air comprising a plate member having a plurality of openings therethrough, said plate member having a flange around each of said openings with said flanges each having a reentry portion defining passageways for air, the plate portion between each of said flanges and their respective reentry portions 40 being rounded to induce crowding of air into the air passageways. 45

EDWARD L. ANDERSON.
